CLAIM

The ornamental design for an electronic atomizing device as shown and described.

DESCRIPTION

FIG. 1 is a top, front, and right side perspective view of an electronic atomizing device showing my new design; FIG. 2 is a bottom, rear, and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the electronic atomizing device that form no part of the claimed design.

The unshaded surfaces between solid and broken lines form no part of the claimed design.

1 Claim, 8 Drawing Sheets
